STRIP ELEMENT OF PRINTING-FORMS AND PROCESS OF MAKING THE SAME.

1,237,058.

Specification of Letters Patent. Patented Aug. 14, 1917.

Original application filed October 3, 1914, Serial No. 864,894. Divided and this application filed April 1, 1916. Serial No. 88,334.

To all whom it may concern:

Be it known that I, AMOS L. KNIGHT, a citizen of the United States, residing at Philadelphia, in the county of Philadelphia and State of Pennsylvania, have invented 5 certain new and useful Improvements in Strip Elements of Printing-Forms and Processes of Making the Same; and I do hereby declare the following to be a full, 10 clear, and exact description of the same, reference being had to the accompanying drawings, forming part of this specification, and to the figures and letters of reference marked thereon.

This application is a division of my co-pending application Serial Number 864,894, filed October 3rd, 1914, now Patent No. 1,222,415, April 10, 1917, the said application describing and claiming a form of apparatus which may be employed for carrying out the process and producing the article forming the subject matter of the present application.

This invention relates to elements of printing forms and more particularly to strip material thereof such as rules, leads and the like and the principal object thereof is to produce economically such strips from metal commonly employed in the type casting art 30 for casting type characters and known as type metal.

In the practical making of the strip material of the present invention it was found to be of great importance, especially with strip material provided with a printing surface, to follow a process in which, generally set forth, the molten type metal is forced into a suitable cavity, one of the walls of which constitutes a matrix or die to determine 35 the facial characteristics of the finished strip, the metal when congealed being fed forwardly to permit the entry of the next increment and to close the exit of the cavity, the above operations being repeated 40 successively to produce a strip of the desired length.

The product of such process is, as will be readily understood, a strip of type metal of definite width and depth and of indefinite length, which is formed of successively congealed sections fused together to form an integral structure. Each section after congealing becomes melted in the region of

the end thereof which forms the end wall of the mold, by contact with the molten metal 55 subsequently injected, and the melted portion of the congealed section and the injected molten metal thereafter congeal to form a new section fused to the previously congealed section. The injection being preferably cross-wise of the strip and introduced under pressure to impinge against the matrix bearing wall of the cavity insures the production of strip sections which are substantially solid throughout, especially along the 60 surface defined by the matrix against which the molten metal impinges. Gas in the metal and all air trapped in the cavity are driven away from the matrix forming wall by the impact of the molten metal and are either 65 imprisoned ultimately in the portions of the strip section remote from the matrix wall or are forced, as in the preferred manner, out of the strip cavity or mold into the gate to be described hereinafter.

The above process is of peculiar advantage in producing printing strip material because it is analogous in principle to the universally employed injection method of making individual types and is productive of strips as 80 accurate in dimensions, measured for example in points, and as perfect with respect to printing surface as are type produced by the said injection method. Moreover this strip material is capable of being produced 85 by machines for casting type, said machines being altered in only a few respects as illustrated, for example, in the said Patent No. 1,222,415.

In the accompanying drawings,—

Fig. 1 is a sectional view in a plane longitudinally of a mold substantially on the line 1—1 of Fig. 2.

Fig. 2 is a transverse section substantially on the line 2—2 of Fig. 1.

Fig. 3 is an elevation looking at the left hand end of the mold and associated parts shown in Figs. 1 and 2, but omitting the mold blade operating bar.

Fig. 4 is a section in a horizontal plane, 100 with the parts shown in a more or less diagrammatic manner, through the mold and associate parts to illustrate the operation of the mold blade and cutter.

Figs. 5 and 6 are diagrammatic illustrations of the strip material of the present

invention in the form of a portion of a printer's rule and the mold blade which cooperates therewith to advance the rule and to form the space for the reception of succeeding increments of molten metal.

Figs. 7 and 8 are perspective views looking at opposite sides of a short section of printer's lead, made in accordance with this invention.

10 Like letters of reference in the several figures indicate the same parts.

For convenience and accuracy of construction the mold is preferably a built-up structure and embodies a mold base 3 formed 15 with a channel therethrough in the direction of the movement of the mold blade, thus providing front and rear upwardly extending portions 4 which are connected across the top of the mold by tie bars 5. There are 20 suitable coöperating shoulders and connecting screws and the shoulders are preferably formed by grooves 6 in the mold base in which projections 7 on the tie bars seat, whereby an exceedingly rigid structure is 25 formed and one capable of being finished with a high degree of accuracy by known economical shop methods. Confined within the channel extending through the mold base are the type blocks between which the 30 cavity for the reception of the molten metal is formed, and these type blocks are preferably in the form of bars which extend out at each end of the mold base and are adapted for the reception, between such extended portions, of point blocks which will determine the width of the mold cavity and consequently the point size of the element being cast. The rear type block 8, is preferably formed with a smooth inner face and 40 constitutes one wall of the mold cavity as well as the wall of the passage in which the mold blade works and of the exit opening through which the formed element is ejected. The front type block may be of similar 45 construction and arranged to be placed in opposition thereto, but it is preferably formed in two sections 9 and 10 for convenience in manufacture, so as to provide at one side of the mold cavity a channel and 50 exit opening through which air and a portion of the molten metal from the mold cavity may escape, in the form of a more or less spongy mass which, for convenience may be called a gate, lying at one side of the element and adapted to be subsequently levered therefrom. The upper front type block 9 substantially corresponds in outline to the upper half of the rear type block 8 and the lower front type block 10 substantially corresponds in outline to the lower half of the rear type block 8, while between the two sections is formed a narrow space 11, and this space widens out within the type block in the form of a channel which is dove-tail or triangular in cross

section, as indicated at 12. The said channel 12 and entrance slot 11 are preferably slightly tapered, or of increasing cross section toward the exit end of the block.

The blocks 8, 9 and 10 are placed face to 70 face in the mold base with the projections 13, 14, 15 and 16 in position against the ends of the mold base and sides of the tie bars respectively, as shown clearly in Fig. 1, while between the projections there are 75 placed point blocks 13^a, 14^a, 15^a and 16^a which are of a thickness corresponding to the point size of the element to be cast and thus define the width of the mold cavity.

Where the front type block is made in two 80 sections as hereinbefore described, the upper section 9 is preferably made rigid with the lower section 10 by being fixed accurately thereto and supported by an upwardly extending portion 10^a of the section 10 to which 85 it is connected by screws or other suitable fastenings, as will be readily understood by an inspection of Fig. 2, which shows these parts in cross section.

The two type blocks forming between 90 them the mold cavity, are positioned laterally of the mold base by a backing plate 17 in rear of the rear type block and by a pressure screw 18 passing through the front projection 4 of the mold base and adapted 95 to bear against the front type block. This pressure screw in the preferred construction is operated periodically in time with the feeding of the element being cast, to clamp the sides of the mold cavity together 100 during the casting operation and to release such pressure during the feeding of the element forwardly in the mold cavity as described in the before-mentioned patent.

The bottom of the mold cavity is formed 105 by the mold base, and is provided with a nozzle opening 20 (Fig. 1) through which the molten metal is injected into the mold cavity from a nozzle 20^a having its opening slightly inclined. The top of the mold cavity is formed by a matrix or member which gives shape to the upper face of the element being cast, and where printers' rules are to be formed, this matrix, indicated in the drawings at 21, is provided in its lower face 110 with a groove 22 of proper cross sectional shape to give form to the printing edge of the rule, but it will be understood that one or more of such grooves may be formed in the matrix, depending upon the character 115 of the printing surface desired.

The matrix 21 is adapted to seat against a matrix abutment 23 mounted on the upper face of the rear type block and it is positioned against such abutment by a locating 120 plate 24 resting on the front type block between the tie bars. The matrix is held firmly in position by a matrix clamp 25 having two surfaces 25^a for coöperation with one edge and the top of the matrix, and an 130

inclined surface 25^b for coöperation with a corresponding inclined surface on the matrix abutment 23, whereby when the matrix clamp is forced down by its clamping screw 5 26 the matrix will be forced downwardly and against its abutment where it will be held with precision and in such relation to the type block as to prevent any liability of molten metal escaping through the joints.

10 The mold blade 27 is of a thickness which corresponds to the point size of the element being cast and is adapted to reciprocate between the proximate faces of the type blocks from the forward position indicated in Fig. 15 1, where its front edge is just forward of the nozzle opening, to a position in rear of said nozzle opening which will determine the width of the cavity to be filled by molten metal. The movement of the mold blade is 20 preferably so adjusted that when at the rear extreme of its movement its upper edge will register with the rear end of the groove in the matrix, although the range of movement is susceptible of adjustment.

25 The forward end of the mold blade, which, when retracted, forms the rear end wall of the mold cavity, is shaped to give the desired conformation to the rear edge of the type metal when congealed and it has been 30 found desirable in practice to give the rear edge of the type metal a conformation which will facilitate the fusion of the metal with the next increment injected into the mold cavity. It is for this reason that the upper 35 portion of the mold blade is curved rearwardly, to thereby form an overhanging or inclined face at the rear edge of the congealed type metal along and against which the inflowing molten metal will travel in 40 filling the mold. The relation of this rear edge of the type metal to the incoming jet of molten metal will be understood from an inspection of Fig. 1 which shows the front end of the mold blade in its forward position, and consequently said front edge conforms to the shape of the rear edge of the type metal which has been advanced by the forward movement of the mold blade. Owing to this formation, the rear edge of the 45 50 congealed metal is subjected to the direct contact of the incoming metal which constantly travels along said edge until the mold cavity is filled, and it is believed that this formation also materially assists in discharging the air from the mold cavity during the entrance of the molten metal inasmuch as any tendency toward a cellular formation or the formation of cavities in the casting is always found to exist at a point 55 considerably below the upper edge and consequently the upper edge is perfect and solid so as to present a proper printing surface.

The provision of the transverse opening 60 into the channel at one side of the mold cavity permits of the complete discharge of

all air from the cavity and the making of a casting solid throughout. In practice the best results have been secured in the making of leads and rules when this opening extends clear along the side of the cavity, and is located at or slightly below the center of the cavity. 70

The metal which enters the channel and forms the gate is connected with the side of the element being cast by a very thin attachment, and it is preferably fed out of the channel simultaneously with the element to which it is attached. Such feeding movement of the gate is preferably effected by a gate pusher 28 conveniently operated 75 directly by the mold blade; the connection between the gate pusher 28 and mold blade being formed by a foot 29 on the rear end of the pusher which enters a socket or opening 30 in the mold blade. 80

At its rear end the mold blade 27 enters the mold between the upper and lower mold blade shoes 31 and 32, respectively, and its forward movement is arrested by a mold blade stop 33, extending into the usual opening in the mold blade and attached to the mold blade base by a screw 34. A mold blade stop of this character leaves the opposite side of the mold blade exposed for the attachment of the mold blade operating bar 95 35. The bar 35 at its forward end enters a recess 37 in the type block at the side of the mold blade, and is pivotally connected to the blade by a transverse stud or pin 36.

The rule being cast issues from between the type blocks and passes through a friction clamp one member of which is a gate shear serving to detach the gate from the side of the element and to form a smooth face on the side should there be any roughness or projecting metal thereon. The gate shear is shown at 44, Fig. 4, while opposed to the flat face of said gate shear is a friction block 45 advanced by spring pressure through the medium of a spring 46 located 100 within a bore in the block 45 and adapted 105 to be held up to its work by a plunger 47 forming the inner end of a friction clamp adjusting screw 48.

Assuming that the mold blade has advanced, pushing before it the portion of the printer's rule previously cast, and has retracted or is in the act of retracting to leave a space between the end of the mold blade and rear edge face of the portion of the rule 110 already cast, the pump mechanism comes into operation to bring the nozzle of the pump into the opening 20 and inject a quantity of molten metal sufficient to fill the mold cavity and to force a portion of the molten 115 metal together with the air previously in the cavity out into the channel at the side of the cavity. In passing into the mold cavity the molten metal flows along the edge face of the previously congealed metal of the rule 120 125 130

- and is deflected thereby directly against the matrix wall of the cavity so as to set up a swirling movement in the cavity. The impingement and flow of the molten metal 5 against and along the face of the congealed metal raises the heat of the latter to a point where fusion will take place and effects a perfect union of the two increments or portions of the metal.
- 10 Just before or during the time the metal is being injected and congealed in the mold cavity the actuating lever is operated to set up the pressure screw 18 on the type blocks so as to clamp all of the parts tightly together and as soon as the metal is congealed this pressure is withdrawn by the reverse movement of the actuating lever 58 and the mold blade is immediately advanced to feed the casting forwardly.
- 15 These operations are repeated in succession until the desired length of rule has been cast and as the rule issues from between the clamps the gate at the side thereof is severed and drops down into the melting pot where
- 20 it is melted for subsequent use.
- 25 A diagrammatic representation of the operation is found in Figs. 5 and 6 of the drawing, wherein the completed rule is indicated at 65, the severing of the gate from the side of the rule at 66, and the end of the mold blade in its advanced position after having fed the rule forwardly at 67. When the mold blade retracts to the position indicated in Fig. 6, it leaves a space 68 in which
- 30 the subsequent casting is effected, and this space, it will be understood, may be regulated in size by the adjustment of the movement of the mold blade and by the introduction of different point blocks and mold blades where the point size is to be changed, as well as by the substitution of different matrices where the style of the printing surface is to be changed or where the printing surface is to be entirely eliminated and
- 35 shoulder high or low elements formed.
- 40 By giving the forward end of the mold blade a curvature such as shown, any tendency of the metal to wedge up against the matrix is effectually overcome.
- 45 The lead or rule strip which is produced by the process described is, when it issues from the machine, a distinctive finished product; that is to say, it is a strip which is of the proper transverse dimension, for use in a
- 50 form of printing type. The face or that edge which corresponds to the face of the type is a cast face and the surfaces of the strip at the sides are cast surfaces which in appearance and function correspond sub-
- 55 stantially to the appearance and function of the face and surfaces of ordinary undressed cast type, and consequently require no planing, dressing or finishing, either to give the proper transverse dimension or face or surface finish. The strip product is thus
- 60 sharply distinguished from prior lead and rule strip material which, as heretofore made by the rolling extrusion or machining processes, invariably presented surfaces which were not cast surfaces but were dressed surfaces. The process of the present invention has made practicable the production of lead and rule strip material formed of type metal or soft metal and of any desired length, which strip material is more advantageous 70 and desirable under modern conditions than is the ordinary brass strip material.
- 65 The distinctive characteristic of the material produced by the present process is due to the fact that the face and surfaces are cast 75 surfaces, that is to say, surfaces which are, during the time the metal is congealing, confined within accurately dimensioning mold faces and therefore present the appearance of cast surfaces easily recognizable by those 80 skilled in the art, and one characteristic appearance of which is shown in Figs. 7 and 8 of the accompanying drawings.
- 70 In these figures of the drawings, the portions of the surfaces indicated at R are 85 slightly roughened or frosted while the portions of the surfaces indicated at S are smooth or substantially free from roughness or frosting. It is, of course, desirable that the face of the strip, especially where the 90 face is intended for use as a printing face shall be as smooth and as uniformly regular as it is possible to make the same, and in practice it is found that where the molten metal is caused to congeal in contact with a 95 matrix, this desirable result can be accomplished. Just the causes which produce the characteristically distinctive appearance of a cast surface are not altogether clear, but apparently the distinctive appearance is due to 100 a combination of causes, for example, shrinkage of the molten metal, while congealing in the mold will produce a certain ruffling or frosting of the surface throughout a part of the section or increment which is congealing, 105 although in some portions the roughened appearance is apparently due to the flow or movement of the metal while in a mushy or semi-fluid condition, while the parts of the metal which remain in intimate contact with 110 the surface of the mold from a time when the metal is thoroughly fluid, until the same is congealed apparently produces the bright or smooth areas. Regardless of the reason for the distinctive appearance, the surfaces are 115 distinguishable as cast surfaces even though they may and frequently do have longitudinal striations or scratches due to the passage of the material through the holding parts of the apparatus subsequent to the 120 congealing of the sections or increments in the mold cavity.
- 125 The several increments or sections which go to make up the complete strip are congealed in the mold cavity successively and merge 130

one into the other by a process of fusion. Thus, there is produced under ordinary circumstances, a repetition of the pattern of the cast surfaces which distinctively defines the successive increments and enables the product to be at once distinguished from the products of processes previously known in the art.

What I claim is:

1. A finished type metal strip to form a lead or rule element in a form of printing type, composed of successively congealed sections of metal merged by fusion one into the other with finished cast side surfaces showing the sectional formation and with a cast face.

2. A finished type metal strip to form a lead or rule element in a form of printing type, composed of successively congealed increments of metal forming sections each with finished cast side surfaces showing the sectional formation and with a cast face, the several sections being merged one into the other to form an element of any desired 25 length.

3. The method of producing a strip of material for use in a form of printing type and having finished cast surfaces which consists in congealing successive increments of 30 molten metal, while confined in a mold cavity having finished internal surfaces and with each succeeding increment in contact with a previously congealed increment, whereby the increments are merged by fusion, and intermittently feeding the congealed metal forwardly out of the mold cavity.

4. The method of forming a distinctive finished strip of material for use in a form 40 of printing type which consists in intermittently forcing increments of molten metal into a mold cavity the exit to which is closed by the congealed metal forming the strip, intermittently feeding the metal forwardly 45 through the exit of the mold cavity and in causing the molten metal to congeal in the mold cavity during the intervals between feed movements.

5. The method of forming a strip of type 50 metal having finished cast surfaces and adapted for use in a printing form, which consists in casting the same in successive sections into a mold cavity having finished internal surfaces, with a rear edge of a preceding section in direct contact with the molten metal of the succeeding section, whereby the sections are caused to fuse together, due to the inherent heat of the metal being cast, and intermittently feeding the

sections forwardly out of the mold cavity 60 when congealed.

6. The method of forming a distinctive finished continuous strip of metal for use in a form of printing type, which consists in intermittently forcing molten type metal 65 into a mold cavity the exit to which is closed by the congealed metal of a previous increment, causing the succeeding increments to unite by fusion, intermittently feeding the metal forwardly through the exit of the 70 mold cavity and in causing the molten metal to congeal in the mold cavity during the intervals between feed movements.

7. The method of forming a distinctive finished continuous strip of metal for use in 75 a form of printing type, which consists in forcibly injecting an increment of molten type metal into a mold cavity, the exit to which cavity is closed by the congealed metal of a previous increment, causing the proximate portions of the two increments to unite by fusion, allowing the increment of molten metal to congeal in the mold cavity, then feeding the congealed and united increments forwardly to permit the entry 85 of the succeeding increment and in repeating said operations to form a finished strip of the desired length, with finished cast surfaces.

8. The method of forming a continuous 90 strip of material for use in the printing art, which consists in making successive individual castings each having an edge, a portion of which edge extends rearwardly of another portion thereof, retaining said 95 edge in position to form a molding face for the next succeeding casting, whereby the molten metal of the next succeeding casting will flow against said edge, and in continuing said successive operations until 100 the length of the strip desired is produced.

9. The method of forming a continuous strip of material for use in the printing art, which consists in making a type metal casting having a rear edge which is extended 105 rearwardly to form an overhanging face, making a second casting having a similar rear edge, said second casting being fused with the rear edge of the first casting by directing the molten metal of said second 110 casting against and causing it to flow along said rear edge of the first casting and continuing the operation of casting and fusing each successive casting to the rear edge of the preceding casting, until the length of 115 strip desired is produced.

AMOS L. KNIGHT.
